UNITED STATES PATENT OFFICE.

LEO RUBINSTEIN, OF VIENNA, AUSTRIA.

MACHINE FOR DRYING VENEERS.

Application filed October 1, 1927, Serial No. 223,331, and in Austria October 9, 1926.

The invention relates to a machine for drying veneers in which the drying is effected by means of moving heaters. Heretofore the drying of veneers by means of moving heaters was effected in such a manner that the moving heaters were moved along stationary veneers or piles of veneers. This method of drying requires many hand operations and implies a great expenditure in time and 10 labour.

The object of the invention is to carry out the drying of veneers by means of moving heaters in a simple and reliable manner by a machine and to provide a machine capable of 15 reliably drying veneers of different lengths and thicknesses as well as of different degrees of moisture with the best drying results. This object is attained according to the invention by providing the machine with devices for moving the veneers along the moving 20 heaters.

In the drawings a constructional form of the machine is illustrated by way of example.

Fig. 1 is a side elevation and Fig. 2 is a plan view of the machine. Fig. 3 is an elevation partly in section on a larger scale of the mechanism for feeding the veneers and of the arrangement of the heaters. Fig. 4 is a section on the line IV—IV Fig. 3. Fig. 5 is a 25 section on the line V—V Fig. 3. Figs. 6 and 7 show the heater in side elevation and plan view respectively. Fig. 8 is a section on the line VIII—VIII Fig. 6 on a larger scale. Fig. 9 is a side elevation on a larger scale of the cooling apparatus provided at the end of 30 the machine. Fig. 10 is a plan view of Fig. 9.

The machine comprises a plurality of moving heaters 1, 2, 3, 4, 5, 6 past which the veneers to be dried are moved. 10, 11, 12, 13, 40 14, 15, 16 and 20, 21, 22, 23, 24, 25 are mechanisms for moving the veneers past the moving heaters 1 to 6. These mechanisms consist of feeding devices 10, 11, 12, 13, 14, 15, 16 engaging the veneers and of guides 20, 21, 22, 45 23, 24, 25 for the veneers. The guides 20 to 25 are arranged opposite the moving heaters 1 to 6. The moving heaters 1 to 6 and the guides 20 to 25 are arranged between the feeding devices 10 to 16.

50 In the constructional form shown by way of example the heaters 1 to 6, the feeding devices 10 to 16 and the guides 20 to 25 resemble each other respectively, hence it is sufficient to describe only one of each of these 55 elements.

As is more particularly shown in Fig. 3 the

feeding devices 10 to 16 consist each of a pair of rollers 30, 31 having their axles 32, 33 journalled in bearings 34, 35. The bearings 34, 35 are slidably vertically in a standard 36. 60 The bottom bearing 35 is adjustable vertically and capable of being locked in position by a screw 38. Thereby the position of the bottom roller may be nicely adjusted in the vertical direction. The upper roller 30 rests 65 on the bottom roller 31 by gravity.

The heaters 1 to 6 consist of heating blocks 40 parallel to the feed rollers 30, 31. The heating blocks being of a considerable length; they are stiffened by stiffening ribs 70 41. The ends of the heating blocks 40 are suspended on the longitudinal beams 45, 46 by means of rods 43, 44. The longitudinal beams 45, 46 are connected by transverse bars 48 to form a slide in the form of a frame. 75 This slide forms the support for all the heating blocks and is reciprocated by an actuating gear 50 as hereinafter more fully described. Rollers 52 are loosely mounted on the transverse bars 48; these rollers run on 80 the guides 53. The guides 53 are vertically slidable in the standards 36 for the bearings and are provided as is shown in Fig. 3 with adjusting inclines 55 resting on inclines 56 of an adjusting frame 58 parallel to the direction of the feed. The adjusting frames are movably mounted in guides 60 of the standards 36 for the bearings and are so connected with each other by rods 61 that all the adjusting frames may be adjusted from a 85 single point.

The mechanism for operating the adjusting frames 58 consists of a hand wheel 63 to the shaft 64 of which worms 65 are secured. The worms 65 engage into worm wheels 66 95 cooperating with actuating screws 67. The actuating screws 67 are connected by the rod 61 to the adjusting frames 58. By means of the mechanism above described the guides for the slide 45, 46, 48 on which the heating blocks 40 are suspended may be adjusted vertically whereby at the same time the heating blocks 40 are adjusted relatively to the guides 20 to 25 for the veneers. 100

The heating blocks 40 are resiliently yieldingly mounted relatively to the guides 20 to 25 of the feed way located opposite such heating blocks. For this purpose the suspending rods 43, 44 (Figs. 4 and 5) are slidably mounted in supporting sleeves 70 of the longitudinal beams 45, 46 and are held above such sleeves 70 by springs 72. The one of the 110

spring abutments 73 is vertically adjustable on the rod 43 or 44 by means of a nut 74. The other spring abutment 76 is screwed on a sleeve 77 threaded on the suspending rod 43 or 44 and secured to the heating block 40 by screws 78. By turning the spring abutment 76 each heating block may be nicely adjusted vertically. By turning the nuts 74, that is to say by adjusting the other spring 10 abutment 73 the tension of the spring 72 may be adjusted.

The heating blocks 40 are provided with heating devices. In the example shown the heating device consists of a steam duct. 15 Channels 80, 81 extend longitudinally through the heating blocks and communicate with each other at one side of the heating block by a connecting pipe 82. At the other side of each heating block connecting pieces or ajutages 83, 84 are provided for establishing communication with the admission and escape of the heating agent. In the example shown the heating blocks 40 are made of some light metal. The 20 channels 80, 81 through which flows the heating agent are formed by tubes 86, 87 of a metal higher specific weight such as brass, iron or the like embedded in the body 40 of light metal. The operative heating surface 25 of each heating block is provided with a covering 88 likewise made of a metal of higher specific gravity for instance of brass. The covering 88 is secured to the light metal block in any suitable manner for instance by 30 screws. The longitudinal edges 89, 90 of the covering 88 are inclined upwards so that the veneer running through the machine may slip in below the covering 88 without sticking.

40 The guides 20 to 25 arranged opposite the moving heaters are provided with plane guide faces 95. The parts 96, 97 of the side edges in the neighbourhood of the pairs of feed rollers are bevelled downwardly. 45 Thereby a smooth running up of the veneer onto the guide faces 95 is secured. The guides are provided with chambers 100, 101 for introducing thereinto a heating agent for instance steam. In the example shown each 50 guide is provided with two steam chambers 100, 101 which on the one side communicate with each other by an opening in the partition 102. On the other side of the heating chambers 100, 101 holes 104, 105 are provided for the admission and the escape of the heating agent. The guides are interposed by means of screws 110, 111, 112, 113 between the standards 36 for the bearings of the pairs of feed rollers in the manner illustrated in 55 Fig. 3. The mode of securing the guides in position permits of a nice adjustment of the same relatively to the bottom feed rollers and thereby also a nice adjustment of the feed path of the machine.

60 The heating of the heaters 1 to 6 and of the

guides 20 to 25 in the example shown is such that middle heater 4 and the middle guide 23 opposite to such heater have the highest temperature while the temperature of the heaters and of the guides successively decreases towards both ends. For this purpose the supply 120 for the heating agent is connected on the one hand to the steam chambers of the middle guide 23 and on the other hand by means of a flexible hose 121 to a duct 123 connecting the heater 3 with the heater 4. Moreover the chambers 100, 101 of the middle guide 23 are connected by ducts 125, 126, 127 and 128, 129 respectively with the guides 22, 21, 20 and 24, 25 respectively while the 70 heaters are connected with one another beginning with the middle heater by communicating ducts 123, 132, 133, 134, 135. The heating agent escapes from the guide 20 through a duct 137, from the guide 25 through 80 a duct 138, from the heater 1 through the flexible hose 139 and from the heater 6 through the flexible hose 140. 141 designates the heating agent escape duct common to heaters and guides. The fact, that heating agent flowing in succession through the guides and heaters beginning with the middle guide 23 and the middle heater, secures that the temperature of the heaters and of the guides is lower at the beginning and at the end of the feed path than in its middle.

The machine is further provided with a cooling apparatus, which effects a cooling of the heated veneers dried in the machine. The cooling apparatus consists as is shown 100 in Figs. 1 and 2 of feeding devices 17, 18 and of cooled guides 26, 27 for the veneers. The feeding devices 17, 18 are similar in construction to the feeding apparatus 10 to 16 and consists of pairs of rollers 150, 151 journaled 105 in standards 152. The guides 26, 27 consist of plane guide plates 155 having arranged below them cooling channels for instance a cooling coil 157. The cooling coils of the guides 26, 27 communicate with each other by a connecting pipe 190. 191 is the supply duct for the cooling agent, 192 is the escape duct therefor.

The driving mechanism of the machine consists of a driving gear 50 for bringing 115 about the reciprocating movement of the heaters. The driving gear for the pairs of feed rollers consists of a step pulley 160 the shaft 161 of which carries a worm 162. The worm 162 engages into a worm wheel 163 secured to a shaft 165 journaled laterally of the bottom rollers of the pairs of feed rollers. On the shaft 165 bevel wheels 166 are mounted which cooperate with bevel wheels 167 of the bottom rollers 31 and 151 respectively. The 120 rotary movements of the bottom rollers 31 and 151 respectively are transmitted to the top rollers by means of pairs of spur wheels 170, 171.

125 The driving gear of the heaters 1 to 6 con- 130

sists of two crank gears 50 connected by links 175 to the longitudinal beams 45, 46 of the slide carrying the heaters 1 to 6. The cranks 50 are mounted on a shaft 176 carrying the 5 step pulley 177 and a belt pulley 178 and an idle pulley 179. The step pulley 177 drives the step pulley 160 by means of a belt 180.

On actuating the pulley 178 on the one hand the cranks 50 and on the other hand 10 the pairs of feed rollers are revolved through the medium of the parts 177, 180, 160, 161, 162, 163, 165, 166, 167. The cranks 50 bring about reciprocating movements of heaters 1 to 6. In these reciprocating movements the 15 heaters are exactly guided by the rollers 52, 52. The veneers to be dried are introduced into the first pair of feed rollers and are engaged successively by the feed roller pairs and fed. The onward moving veneers are guided 20 in the spaces between successive pairs of feed rollers by the heated guides 20 to 25 and then by the cooled guides 26 and 27. The heaters 1 to 6 are reciprocated by means of the cranks 50 above the veneers thus moving them on- 25 ward and bringing about the drying of the veneers. The heaters may either be in contact with the veneers or may exert their drying action while moving at a slight distance from the veneers. In the present machine the 30 veneers therefore move between the reciprocating heated heaters 1 to 6 and the stationary likewise heated guides 20 to 25.

The temperature of the heaters and heated 35 guides at front end in the direction of the feed of the veneers being lower than that of the heaters and heated guides in the middle of the feed path, the drying is not sudden but gradual. Thereby the veneers are particularly spared from injury. Moreover the 40 temperature gradually decreases from the middle heater and the middle heated guide towards the end of the feed path, thereby a less difference of temperature is secured on passing from drying to cooling and the 45 veneers are spared to the greatest possible extent. By turning the hand wheel 63 all the heaters may be adjusted in common and from a single place relatively to the stationary guides 20 to 25 and hence for the thickness 50 of the veneers to be dried. On turning the hand wheel 63 all the adjusting inclines 58 are displaced horizontally their adjusting faces 56 slide on the adjusting faces 55 and cause the guides 53 for the rollers 52 of the slide 55 45, 46, 48 to be raised or lowered. By adjusting the spring abutment nuts 76 each individual heating block could be adjusted vertically. The step pulley gearing 177, 180, 160 permits to govern the speed of the forward 60 movement of the veneers relatively to the movements of the heaters and therefore to control the drying.

The machine shown in the drawings is only an example of carrying the present invention 65 into practice. The details of the machine

may also be varied within the scope of the invention set forth; thus for instance the driving gear for reciprocating heaters might consist of an eccentric gearing, a slotted link or the like. Also the heating of the heaters 70 and the stationary guides might be of any kind for instance electric.

The machine above described combines with greatest reliability in operation a compact structure and its costs of making are much lower than those of the known veneer 75 drying machines.

What I claim is:

1. In a machine for drying veneers, the combination of heaters, means for moving 80 the heaters in the direction of the veneers, and means for feeding the veneers to be dried past the said heaters along a feed path.

2. In a machine for drying veneers the combination of heaters, means for moving 85 the heaters in the direction of the veneers, and means for feeding the veneers to be dried past the said heaters along a feed path, such latter means comprising guides located opposite the said heaters and a plurality of feed- 90 ing devices adapted to engage the veneers each of such feeding devices being interposed between two successive guides.

3. In a machine for drying veneers the combination of heaters, means for moving 95 the heaters and means for feeding the veneers to be dried past the said heaters along a feed path such latter means comprising a plurality of guides located opposite the said heaters, means for heating the said heaters and guides and means for keeping the temperature of the heaters and guides in the middle of the feed path at a higher level than at the ends of such feed path.

4. In a machine for drying veneers the 100 combination of heaters, means for moving the heaters and means for feeding the veneers to be dried past the said heaters along a feed path such latter means comprising a plurality of guides located opposite the said heaters heating chambers individually associated to the said guides means for connecting in series the heating chambers of the said guides beginning at the middle of the said feed path and ending at the ends of such feed path and means for supplying a fluid heating agent to the heating chambers at the middle of the feed path and for drawing off the heating agent at the ends of the said feed path. 110

5. In a machine for drying veneers the combination of heaters, means for moving the heaters and means for feeding the veneers to be dried past the said heaters along a feed path, such latter means comprising a plurality of guides located opposite the said heaters and means for adjusting all the heaters simultaneously relatively to the said guides. 115

6. In a machine for drying veneers the combination of heaters, means for moving 120

the heaters, means comprising a slide carrying the heaters, guides for such slide and means for adjusting the said slide guides, with means for feeding the veneers past the 5 said heaters along a feed path.

7. In a machine for drying veneers the combination of heaters, means for moving the heaters, such means comprising a slide carrying the heaters, guides for such slide 10 and means for adjusting the said slide guides, such adjusting means comprising inclines on the slide guides adapted to engage with the inclines on the said slide and means for simultaneously adjusting the slide inclines, 15 with means for feeding the veneers past the said heaters along a feed path.

8. In a machine for drying veneers the combination of heaters, means for moving the heaters, such means comprising a slide 20 consisting of longitudinal beams, transverse bars connecting such longitudinal beams means for suspending the said heaters on the said longitudinal beams, with guides for the slide, such guides being adapted to cooperate with 25 the said transverse bars, and means for feeding the veneers past the said heaters along a feed path.

9. In a machine for drying veneers the combination of heaters, means for heating 30 such heaters, comprising heating channels adapted to receive a heating fluid, connections between the heating channels of successive heaters connecting such channels in series beginning at the middle heater and ending 35 at the end heaters of the series, a supply pipe for fluid heating agent leading to the middle heater and escape pipes for the fluid heating agent from the end heaters and of means for feeding the veneers past the said heaters along 40 a feed path.

10. In a machine for drying veneers the

combination of heaters, means for moving the heaters in the direction of the veneers passing through the machine, and means for feeding the veneers to be dried past the said 45 heaters along a feed path and of a cooling device for the veneers located at one end of the feed path.

11. In a machine for drying veneers the combination of heaters, means for moving 50 the heaters and means for feeding the veneers to be dried past the said heaters along a feed path and of a cooling device for the veneers located at one end of the feed path such cooling device comprising a feed device and plates 55 provided with channels for a cooling agent to pass through such cooling plates being arranged in the feed path of the said feed device.

12. In a machine for drying veneers the 60 combination of heaters, means for moving the heaters and means for feeding the veneers to be dried past the said heaters along a feed path and of a cooling device for the veneers 65 located at one end of the feed path such cooling device comprising a feed device and a plurality of plates provided with channels for a cooling agent to pass through such cooling plates being arranged in the feed path of the 70 said feed device and the said channels of successive cooling plate being connected with each other.

13. In a machine for drying veneers the combination of heaters, means for moving 75 the heaters and means for feeding the veneers to be dried past the said heaters along a feed path and means for varying the speed of the feed of the veneer with relation to the speed of movement of the heaters.

In testimony whereof I affix my signature.

ING. LEO RUBINSTEIN.
